(57) **CLAIM**

The ornamental design for chair, as shown and described.

DESCRIPTION

FIG. 1 is a left side elevation view of the chair showing my new design;

FIG. 2 is a right side elevation view thereof;

FIG. 3 is a front view thereof;

FIG. 4 is a rear view thereof;

FIG. 5 is a top plan view thereof; and,

FIG. 6 is a bottom plan view thereof.

The broken line showing of portions of the chair is included for the purpose of illustrating environmental structure and forms no part of the claimed design.
